HEAT EXCHANGER

Julius Naab, Easton, Pa., assignor to Ingersoll-Rand Company, New York, N. Y., a corporation of New Jersey

Application December 4, 1947, Serial No. 789,619

2 Claims. (Cl. 257—220)

1

This invention relates to a heat exchanger, and more particularly to an aftercooler-separator unit adapted to be used in connection with air driven machines and tools.

It is a well established fact that the expansion of compressed air, in air tools, causes a considerable decrease of temperature of the air within the tool which results in condensation of any moisture in the air. Such moisture causes rapid deterioration of the metals in the tool and in some instances, the decrease in temperature is sufficient to cause the formation of ice in and around the exhaust port of the tool thereby lowering its efficiency.

In order to avoid these disadvantages the present practice is to eliminate any moisture present in the compressed air before its delivery to the air tool by passing the compressed air through an aftercooler to condense such moisture and thence through a separator in which the condensate is removed from the compressed air. However, such practice presents a disadvantage whenever floor space is limited in that the aftercooler and separator are in many instances greater in length than the compressor to which they are adapted. Also, in the event that it is necessary to clean the aftercooler, the air tools must be shut down until the cleaning operation is completed or if continued operation of the tools is desired, a complicated and expensive by-pass system for the compressed air must be installed around the aftercooler.

It is, accordingly, one object of my invention to reduce the floor space occupied by a cooler and separator by combining them into one compact unit.

Another object is to enable substantially uninterrupted operation of the air tools by constructing a cooler-separator unit which will allow operation of the tools after removal of the cooling unit.

A further object is to present a cooler-separator unit in which the cooling unit may be removed with ease.

Other objects will be in part obvious and in part pointed out hereinafter.

In the drawings accompanying this specification and in which similar reference numerals refer to similar parts,

Figure 1 is a vertical elevation, partly in section, of the cooler-separator unit constructed in accordance with the practice of the invention.

Figure 2 is a view taken through Figure 1 on the line 2—2, and

Figure 3 is a vertical elevation of the removable cooling unit.

Referring to the drawings, a cooler-separator unit constructed in accordance with the practice of the invention and designated in general by 10, comprises a housing 11 encircling a heat exchang-

2

er 12 having compressed air inlet and outlet openings 13 and 14, respectively. As shown, the heat exchanger includes a tubular wall 15 preferably positioned coextensively and concentrically within the housing 11 to define a cooling chamber 16 which entirely encases a removable cooling unit 17.

The compressed air inlet 13 and an outlet 14 for the chamber 16 are, in the present form of the invention, positioned at opposite end portions of the walls 15 thereby requiring the compressed air flowing through the chamber 16 to pass along the entire length of the cooling unit 17. The outlet 14, positioned in the lower portion of the unit 10, communicates with a chamber 18 which is formed between the wall 15 and the housing 11 to serve, in this instance, as a separator chamber 18 to receive the discharge of compressed air from the heat exchanger 12 for the removal of condensate from such air. The condensate is drained from the separator chamber by a drain pipe 19 at the lower portion of the housing 11, and the dry compressed air escapes through an outlet 20 at the upper portion of the housing.

The outlet 20 is shown as having a portion which extends into the chamber 18 and is tapered downwardly toward the wall 15, or, more specifically the inner end surface 34 of the outlet 20 lies in a plane inclined with respect to the wall 15 and in a direction away from the inlet end of said wall 15, thereby requiring dry air escaping through the outlet 20 to come into intimate contact with the upper or warmer portion of the wall 15. This construction presents several advantages in that the dry air is heated somewhat and expands, thereby regaining at least part of the volume decrease occurring during the cooling process, and also the air escaping from the separator chamber necessarily conducts some heat from the wall 15.

Adapted to seat on the ends of the housing 11 and secured thereto by bolts 21, are water boxes 22 which enclose the ends of the cooling chamber 16 and have a portion extending thereinto for conveying cooling water to the unit 17. Encircling the inmost ends of the water boxes 22, at their points of connection with the unit 17, are sealing rings 23 to prevent leakage of water from the boxes 22 and to prevent leakage of pressure fluid into the boxes 22 from the cooling chamber 16. In this instance, a pair of such rings are supplied for each box, and vents 24 in the water boxes 22 are positioned between the rings to enable immediate detection of any leakage which may occur around the rings.

External abutments 25 around the water boxes 22 have elevated portions to provide steps 26 which are designed to engage similar steps 27 on the ends of tubular headers 28 of the cooling unit 17. The headers encircle the inmost ends

of the water boxes 22 and have closed ends with holes therein to receive longitudinally disposed tubes 29 which serve to cool the compressed air flowing through the chamber 16. In furtherance to this end a water supply conduit 35 is connected in the outer end of the box 22 positioned at the air inlet end of the cooler-separator-unit for supplying a cooling medium, such as water, to that box. From said box 22 water is supplied to the cooling unit and passes through the tubes 29 and is discharged therefrom into the box 22 at the opposite end of the unit. The water circuit is completed by a conduit 36 connected to the outer end of last said box 22 which conduit 32 serves, in this instance, as a cooling water discharge passage for the unit.

In order to extend further the flow path of the compressed air through the chamber 16 and to bring it into repeated intimate contact with the tubes 29, the cooling unit is provided with a series of baffles 30 and 31 which extend transversely of the tubes 29 and are arranged to require the compressed air flowing through the casing to follow a sinuous or serpentine course. That is to say, the baffles 30 and 31 are arranged in a staggered fashion with the baffles 30 adapted to seat against the left inner surface of the wall 15 and the baffles 31 seat on the opposite surface of the wall. The baffles are somewhat shorter in length than the diameter of the casing thereby allowing the compressed air to flow around their free ends. To insure further that compressed air flowing through the chamber 16 is brought into intimate contact with the tubes 29 and to increase the cooling area presented to such air, the tubes 29 are provided with exterior fins 32, which, for the sake of simplicity, are shown only at the upper end portion of the tubes 29.

The flow of compressed air through the chamber 16 is further confined to the space adjacent the tubes 29 by plates 33 arranged in parallelism and attached to the sides of the baffles 30 and 31 and having their ends secured to the headers 28. To insure that the plates 33 are suitably positioned with respect to the inlet 13 and the outlet 14 when the cooling unit is assembled in the chamber 16, unequally spaced holes for the bolts 21 require that the water boxes 22 be mounted in such a manner that when the steps 26 and 27 become engaged, the end portions of the plates 33 form an extension for the inlet 13 and outlet 14 and thereby prevent the flow of compressed air external to the cooling unit 17.

In practice, if it becomes necessary to clean or repair the tubes of the cooling unit 17 and at the same time to continue the use of the air line, in which the unit 10 is connected, it is merely necessary to remove the water box 22 and the cooling unit 17 from the housing 11 and then, by replacing the water box and closing the valves (not shown) on the inlet and outlet pipes for the water boxes or by replacing said pipes with pipe plugs, the unit is in condition to allow the flow of compressed air therethrough.

It will now be readily appreciated, from the above description, that I have presented a cooler-

separator unit which is unusually compact and, therefore, occupies only a small area of floor space and has its parts conveniently arranged to permit ease in disassembly and assembly thereof. While I have shown and described the preferred form of my invention, it is to be understood that various changes and modifications may be made therein without departing from the spirit of the invention as set forth in the appended claims.

I claim:

1. In a cooler-separator unit, a housing having a tubular wall therein extending from one end to the other of the housing to define a cooling chamber, a pressure fluid inlet and outlet for the chamber, a removable cooling unit within the chamber and having its end spaced from the ends of said chamber, including a pair of parallel plates for confining the flow of pressure fluid through the chamber to a path within said unit, boxes extending into the ends of said chamber to convey a cooling medium to the cooling unit and to receive such cooling medium discharged from the unit, means on said boxes for positioning said plates to form an extension for said pressure fluid inlet, a separator chamber between the wall and the housing to receive pressure fluid from the cooling chamber, and an outlet for the separator chamber.
2. A cooler-separator unit comprising a housing, a tubular wall extending longitudinally therethrough and having a cooling chamber therein for pressure fluid, a removable cooling unit within said chamber, water boxes enclosing the opposite ends of said chamber for supplying cooling fluid to said unit and receiving cooling fluid discharged from said unit, a separator chamber between said wall and the chamber, an inlet in said wall at one end of the cooling chamber, an outlet at the other end of the cooling chamber in communication with the separator chamber, and an outlet extending radially into the separator chamber in the same transverse plane as said inlet, the inner end surface of the last said outlet being in a plane inclined with respect to said tubular wall and away from the inlet end thereof.

JULIUS NAAB.
